Castrovilli

UNITED STATES PATENT OFFICE.

JOSEPH A. DURNBAUGH, OF WASHINGTON, DISTRICT OF COLUMBIA.

LOCK.

SPECIFICATION forming part of Letters Patent No. 625,249, dated May 16, 1899.

Application filed January 25, 1899. Serial No. 703,348. (No model.)

To all whom it may concern:

Be it known that I, JOSEPH A. DURNBAUGH, a citizen of the United States, residing in the city of Washington, District of Columbia, 5 have invented a new and useful Lock, of which the following is a specification.

My invention relates to locks of the barrel-and-tumbler type, and has for its object to provide a combination-lock wherein the bolt 10 may be actuated by either of two means from the same side of the door or other closure to which the lock may be applied, one of said means being barrel-and-tumbler-controlled and the other being combination-controlled, 15 whereby in the event of losing the tumbler-adjusting key or of the tumbler mechanism becoming disarranged, and thus rendered inoperative, the operator may manipulate the bolt by means of the combination-controlled 20 mechanism, the lock embodying my invention being particularly designed for use in connection with lock boxes and drawers and similar receptacles, but being adapted also for use in connection with doors or, in fact, 25 under any conditions requiring a lock which can be manipulated only by means of a special key or with a knowledge of the combination to which the lock is set.

A further object of my invention is to provide a simple, compact, and efficient relative arrangement of the bolt-controlling devices, adapting the lock to be operated by either of the means provided for that purpose without affecting or requiring the operation of the 35 other means, and also to provide simple and efficient means for setting the combinations by the angular adjustment of the pins which communicate motion from one disk to another of the combination devices.

Furthermore, my invention has for its object to provide simple means for setting the combination devices to operate with either letters or numbers.

Further objects and advantages of this invention will appear in the following description, and the novel features thereof will be particularly pointed out in the appended claims.

In the drawings, Figure 1 is a face view of 50 the exposed portion of a lock constructed in accordance with my invention as seen when applied to a door, such as that of a lock-box.

Fig. 2 is a longitudinal section of the lock, showing the parts arranged for forming letter combinations. Fig. 3 is a rear view. Fig. 4 is 55 a plan view showing in section the dials arranged for forming numeral combinations. Fig. 5 is a face view of the letter-dial. Fig. 6 is a detail view of one of the tumbler-disk studs. Fig. 7 is a similar view of a slightly-modified 60 form of tumbler-disk stud. Fig. 8 is a detail view of a portion of one of the combination tumbler-disks to show the notch for engagement by the detent.

Similar reference characters indicate corresponding parts in all the figures of the drawings.

In the illustrated embodiment of my invention, 10 represents a barrel-casing, in which is mounted a barrel 11, having a key-seat 12, 70 tumbler-pins 13 and tumbler-setting pins 14 being arranged, respectively, in seats in the casing and barrel for operation by means of a key 15, substantially as in the ordinary practice in connection with barrel-and-tumbler locks. The casing may be held in a fixed position by the use of any suitable means adapted to the construction of the door or other device in connection with which the lock may be used; but in the construction illustrated 75 80 the casing is provided with a lateral ear 16, from which project attaching-arms 17, which may be terminally engaged by screws 18, said arms forming a yoke supported by a face-plate 19. The casing is further provided 85 with a reduced spindle portion 20, extending from a shoulder 20^a to the rear surface of the face-plate, and upon this spindle portion are mounted tumbler-disks 21, of which any desired number may be employed, said disks 90 being free to turn independently of the spindle portion upon which they are mounted and being spaced apart by interposed washers or collars 22, which are keyed to said spindle portion by means of webs 23, engaging a 95 longitudinal groove in the spindle portion to prevent rotation thereof.

The barrel extends beyond the plane of the foremost tumbler-disk and through a suitable opening in the face-plate of the lock, and upon 100 the exposed extremity thereof is mounted for revoluble movement a knob 24. In the construction illustrated the front end of the barrel is headed to form a shoulder 25, be-

tween which and the plane of the face-plate is arranged said knob to prevent axial displacement of the latter, and the knob is preferably flanged at its outer end, as shown at 5 26, to receive the head of the barrel; but it will be understood that the details of this portion of the construction may be varied to suit the preferences of the manufacturer.

27 represents the lock-bolt, which is mounted 10 to slide in connection with suitable guides, such as those shown, respectively, at 28 and 29, and carried by this bolt is a finger 30, arranged in the path of the free end of an arm 31, carried by the barrel, said barrel being 15 extended in rear of the tumbler-casing and having the said arm detachably secured thereto against independent rotation. In the construction illustrated the eye of the arm 31 has an interlocking connection with the 20 rear end of the barrel, and axial displacement of said eye is prevented by means of a screw 32, of which the head overlaps the eye at one point. Backward movement of the barrel beyond a normal or initial position is 25 prevented by a fixed stop 33, arranged in the path of the arm 31 and, as illustrated, attached to the lateral projection of the tumbler-casing, and as the bolt is yieldingly held in its extended or locking position by means 30 of an actuating-spring 34 it will be seen that the key-seat of the barrel is normally maintained in such a position as to be readily accessible by the tumbler-adjusting key. Also the above-described finger 30 carries a detent-guide 35, in which is mounted a gravity-detent 36, arranged in operative relation with the tumbler-disks and adapted at its lower edge to engage peripheral notches 37 in said disks when the notches of the several disks 40 are arranged in alinement in the plane of the detent. The yielding detent may be actuated by any suitable means to cause its engagement with the peripheral notches of the disks when the latter are properly disposed with 45 relation thereto; but I prefer to utilize gravity as the actuating force because of the reduction of friction over that which would be exerted by a spring, the absence of a snap or click as the peripheral notches are brought 50 into the plane of the detent, and also the simplification of the construction, and when, as illustrated, the bolt is arranged to operate above the plane of the tumbler-disks I am enabled to locate the detent-guide directly in 55 the vertical plane of the axis of the barrel, and thus utilize gravity as the means of actuating the detent without in any way detracting from the efficiency and accuracy of movement of the several parts of the structure. Said detent is preferably headed or shouldered, as shown at 38, to limit the downward movement thereof, and also to prevent upward displacement I preferably employ a stop-pin 39, transversely spanning the 60 detent-guide and extending through a vertical guide-slot 40 in the detent, as shown in Fig. 2.

The means which I have illustrated for com-

municating motion from one tumbler-disk to the next, whereby all may be rotated in a common direction by means of the front or 70 foremost disk, consist of studs 41, projecting from the faces of the disks and arranged in common paths, and motion is communicated from the exposed operating knob or handle 24 to the front disk by means of a similar stud 75 42. Therefore with the parts constructed as thus far described the bolt may be retracted by inserting into the key-seat a tumbler-pin-adjusting key of the proper construction, and thus communicating motion from the arm 31 80 to the bolt-carried finger 30; or in case of accident to the barrel-and-tumbler mechanism or lacking the proper key the operator may adjust the tumbler-disks by means of the exposed knob to arrange the notches of 85 said disks in registration with the detent to allow the latter to drop into engagement with the notches, whereupon the bolt may be retracted by turning the knob in the proper direction, and thus communicating motion 90 through the front disk and the detent to the arm 30. In practice the notch of the front disk is beveled or rounded at one side to facilitate the engagement therewith of the detent (the other disks being properly positioned) when said foremost disk is turned in one direction; but the other side of said 95 notch is abrupt or radially disposed to provide for communicating motion from the disk to the bolt by advancing the detent in the 100 direction of movement of the bolt. Also the beveling of one side of the notch in the front disk provides for throwing the detent out of engagement with the notches of the disk when said foremost disk is turned in the opposite 105 direction, whereby after the lock has been opened the disks may be turned out of their bolt-releasing positions to prevent future manipulation of the lock without a knowledge 110 of the combination to which the same is set.

In order that the combination may be changed, the positions of the studs by which motion is communicated from one disk to another may be angularly adjusted with relation to the detent-receiving peripheral 115 notches of the disks, and to provide for this angular adjustment I employ a sectional construction of disk, comprising a core 21^a and an encircling rim 21^b, the stud being threaded in a socket 43 in the core near its periphery 120 and the said notches being formed in the periphery of the rim. Each stud, however, in the plane of the disk is provided with a cam-face 44, which when the stud is in one position binds against the inner edge of the rim, 125 and thus locks the latter frictionally against rotation independently of the core, whereas when the stud is in another position the rim is released to allow the required angular adjustment thereof. In the construction illustrated in Figs. 2 to 6, inclusive, this cam-face 130 is provided by flattening the stud at one side, and when the flattened portion of the stud faces the inner edge of the rim the latter is

free to turn, whereas when the stud is turned slightly in either direction from said position it acts as a friction-clutch to lock the rim at the desired adjustment. In the modified construction illustrated in Fig. 7 the stud is provided with an enlargement 45, forming the cam; but the operation is identical with that above described. Each stud may be provided with a key-seat 46 to facilitate turning of the 10 stud in releasing and subsequently locking the rim at the desired adjustment.

In addition to the above-described means for varying the combination I employ a plurality of indicating-dials 47 and 48, the former of which is preferably carried by the above-described knob 24, while the latter, although coaxial with the former, is independent thereof and may be secured to the face-plate of the lock or to the exterior surface of the door 15 in connection with which the lock is used to provide for a movement of the knob-carried dial without affecting that which is fixed in position. A stationary index 49 of any suitable construction (as inscribed upon the face-plate or surface of the door) is arranged adjacent to the periphery of the outer dial 48, and said outer dial, which preferably carries combination-letters, as illustrated, may be arranged to receive rotary motion from the 20 knob by employing fastening devices, such as screws 50, extending through the dial 47 and engaging the dial 48, as indicated in Fig. 2. Also the dial 48 carries an index 51, and when it is desired to use the permutation 25 characters carried by the dial 47 said fastening devices, consisting of the screws 50, may be extended through the dial 48 and engaged with the face-plate or other fixed object adjacent to the plane of said dial to hold the 30 latter against rotation, while allowing the dial 47 to turn independently thereof. In practice I prefer to provide the dial 48 with segmental slots 52, with which said fastening 35 screws engage, whereby angular adjustment of said dial may be accomplished to vary the combination without recourse to the adjustment of the studs of the tumbler-disks. The means described for varying the combinations provide for forming practically an unlimited 40 number of combinations.

It will be seen from the foregoing description that the lock is of simple and compact construction, adapting it to be arranged within a small compass suitable for use in connection with lock boxes and drawers, and that owing to the relation between the parts the bolt may be operated either by means of the barrel or by means of the knob without affecting the other, whereby the lock-box or 45 similar receptacle may be opened either with or without the aid of a key, provided the combination to which the lock is set is known, and, furthermore, it will be seen that the lock may be set for a combination of either letters or numerals, as may be preferred by the operator, and changed either by varying the position of the angularly-adjustable dial 48 or by

varying the relative positions of the disk-carried studs and notches.

It will be understood, furthermore, that in practice various changes in the form, proportion, size, and minor details of construction within the scope of the appended claims may be resorted to without departing from the spirit or sacrificing any of the advantages of the invention.

Having described my invention, what I claim is—

1. A barrel-and-tumbler lock mechanism having its casing provided with a spindle portion, combination tumbler-disks mounted upon said spindle portion, a disk-operating knob, and bolt-operating means actuated respectively by the barrel and the tumbler-disks, substantially as specified. 85

2. A barrel-and-tumbler lock mechanism having its casing provided with a spindle portion, combination tumbler-disks mounted upon said spindle portion, a disk-operating knob, a bolt, and independent connections 90 between the barrel and disks and the bolt, substantially as specified.

3. A barrel-and-tumbler mechanism having its barrel provided with a bolt-operating arm and its casing provided with a spindle portion, combination tumbler-disks mounted upon the spindle portion of the casing, an exposed disk-setting knob, and means for communicating motion from the disks to the lock-bolt, substantially as specified. 100

4. A barrel-and-tumbler mechanism having its barrel provided with a bolt-operating arm and its casing provided with a spindle portion, combination tumbler-disks mounted upon the spindle portion of the casing, an exposed disk-setting knob mounted upon an exposed portion of the lock-barrel, and means for communicating motion from the disks to the lock-bolt, substantially as specified. 105

5. A barrel-and-tumbler mechanism having its barrel provided with a bolt-operating arm and its casing provided with a spindle portion, combination tumbler-disks mounted upon the spindle portion of the casing, an exposed disk-setting knob mounted upon an exposed portion of the lock-barrel and terminally flush therewith, and means for communicating motion from the disks to the lock-bolt, substantially as specified. 110

6. A barrel-and-tumbler lock mechanism having its barrel provided with an arm and its casing with a spindle portion, combination tumbler-disks mounted upon the spindle portion of the casing, a bolt, a bolt-operating arm carried by the barrel, a movable detent 125 carried by the bolt for engagement by the tumbler-disks, and exposed means for adjusting the tumbler-disks, substantially as specified. 120

7. A barrel-and-tumbler lock mechanism having its barrel provided with an arm and its casing with a spindle portion, combination tumbler-disks mounted upon the spindle portion of the casing, a bolt, a bolt-operating 130

arm carried by the barrel, a guide carried by the bolt, a gravity-actuated detent fitted in said guide for engagement by the tumbler-disks, and an exposed disk-setting device, substantially as specified.

8. A barrel-and-tumbler lock mechanism having its barrel provided with an operating-arm and its casing with a spindle portion, combination tumbler-disks mounted upon the spindle portion of the casing, a spring-actuated bolt having a finger arranged in the path of movement of said barrel-carried arm, a movable detent carried by the bolt for engagement by the tumbler-disks, and exposed means for adjusting the tumbler-disks, substantially as specified.

9. A barrel-and-tumbler lock mechanism having its barrel provided with an operating-arm and its casing with a spindle portion, combination tumbler-disks mounted upon the spindle portion of the casing, a spring-actuated bolt having a finger arranged in the path of forward movement of said barrel-carried arm, a stop arranged in the path of backward movement of said arm, a movable detent carried by the bolt for engagement by the tumbler-disks, and exposed means for adjusting the tumbler-disks, substantially as specified.

10. A lock having a bolt, and barrel-and-tumbler bolt-operating mechanism, combination tumbler-disks arranged in operative relation with said bolt, and disk-setting devices movable independently of the barrel, substantially as specified.

11. A lock having a bolt, and barrel-and-tumbler mechanism for operating the bolt, combination bolt-operating tumbler-disks mounted concentrically with said barrel, and exposed means for actuating the tumbler-disks substantially as specified.

12. A lock having a bolt, barrel-and-tumbler bolt-operating mechanism, and combination bolt-operating tumbler-disks, and disk-setting devices mounted coaxially with the tumbler, substantially as specified.

13. A lock mechanism having a sectional tumbler-disk comprising a core and rim, of which the latter is angularly movable independently of the former, and means, consisting of a stud, mounted in one of the disk-sections, for clamping the rim at the desired angular adjustment with relation to the core, substantially as specified.

14. In a lock mechanism, a sectional tumbler-disk having a core and an angularly adjustable rim, and a cam-faced stud revolvably mounted in one of the disk-sections for engagement with the other to clamp the rim at the desired angular adjustment, substantially as specified.

15. In a lock mechanism, a sectional tumbler-disk having a core and a rim angularly adjustable with relation to the core, and a stud threaded in the disk-core, and having a cam-face for frictional engagement with the inner edge of the rim to lock the latter at the desired adjustment, substantially as specified.

16. In a lock mechanism, the combination with bolt-operating tumbler-disks, of a tumbler-disk-setting knob, a plurality of coaxial dials, one of which is carried by said knob, and means for communicating motion from the knob-carried dial to the other, substantially as specified.

17. In a lock mechanism, the combination with bolt-operating tumbler-disks, of a tumbler-disk-setting knob, coaxial dials, one of which is carried by said knob, and the other is independent thereof, and the latter being provided with segmental slots, and means for engagement with said slots, to secure the independent dial at the desired angular adjustment, substantially as specified.

In testimony that I claim the foregoing as my own I have hereto affixed my signature in the presence of two witnesses.

JOSEPH A. DURNBAUGH.
